UNITED STATES PATENT OFFICE.

ANDREW C. ERICKSON, OF LOS ANGELES, CALIFORNIA.

SHOE-POLISHING APPARATUS.

1,230,572.

Specification of Letters Patent. Patented June 19, 1917.

Application filed December 14, 1916. Serial No. 136,949.

To all whom it may concern:

Be it known that I, ANDREW C. ERICKSON, a citizen of the United States, residing at Los Angeles, in the county of Los Angeles 5 and State of California, have invented new and useful Improvements in Shoe-Polishing Apparatus, of which the following is a specification.

This invention relates to a shoe polishing 10 apparatus.

It is the principal object of this invention to provide an adjustable foot rest adapted to support a shoe and guide a polishing cloth thereover while the shoe is being 15 polished.

Another object of this invention is to provide an adjustable turn-table upon which the shoe is adapted to rest and which permits the operator to have free access to all parts 20 of the toe and heel as well as the length of the upper.

Another object of this invention is to provide adjustable guide means for a polishing cloth so that the apparatus may be readily 25 adapted for polishing shoes of different lasts.

It is a further object of this invention to provide a shoe polishing apparatus which is not complicated in its construction and may 30 be readily and adjustably fixed to accommodate shoes of various sizes.

Other objects will appear hereinafter.

The invention is illustrated, by way of example, in the accompanying drawings in 35 which:

Figure 1 is a view in perspective illustrating the shoe polishing apparatus.

Fig. 2 is a view in longitudinal section as seen on the line 2—2 of Fig. 1 and particularly illustrates the revoluble foot plate 40 and the roller adjustment mechanism.

Fig. 3 is a view in transverse section as seen on the line 3—3 of Fig. 1 and illustrates the formation of the base of the apparatus 45 and the disposition of the cloth guide rollers upon each side thereof.

Fig. 4 is a view in transverse section and elevation as seen on the line 4—4 of Fig. 2 and illustrates the roller adjustment mechanism. 50

Fig. 5 is a view in perspective illustrating the polishing cloth with a portion of the length broken away.

Fig. 6 is a fragmentary view of a portion 55 of the foot plate and discloses in detail the

formation of the tangs for preventing the slippage of the foot.

Fig. 7 is an enlarged sectional view as seen through the end of the device and as illustrating the locking device for the roller adjustment. 60

Fig. 8 is a view in perspective illustrating the application of the device as used for polishing the toe of the shoe.

Fig. 9 is a view similar to Fig. 8 illustrating the application of the device as used to polish the instep and heel of the shoe as well as the top. 65

Referring more particularly to the drawings, 15 indicates the base portion of the apparatus which is here shown as comprising a centrally disposed upright 16 formed with concaved sides 17 and 18. The lower portion of the member 15 is formed with horizontally extending side flanges 19 and 20, 70 the upper faces of which form a continuation of the arcuate sides. Mounted upon the top of the upright portion 16 of the base is a pivot plate 21 which is formed with a protrusion 22 adapted to support a rotatable 75 foot plate 23. This plate is formed substantially in the shape of a shoe sole. A pivot screw 24 passes through the protrusion 22 and into the upright 16 to hold the foot plate in a pivotal position, the lower 80 plate being suitably held by screws or nails 85 as desired.

The foot plate is of a length slightly longer than the block upon which it is mounted and overhangs the block at each 90 end, its outer ends being flush with the outer faces of end uprights 25 and 26. These uprights are composed of an outer plate 27 which is formed with an inturned flange 28 which extends around both sides and the top 95 of said member. The lower side is formed with an inturned flange 29 by which the plate is secured beneath the body portion 15 of the apparatus. A series of screws 30 are provided to hold the plate in fixed relation 100 to the device. The upper inturned flange of the plate is substantially arcuate in contour and fits within an outturned flange 31 formed upon an inner plate 32 which is directly secured to the ends of the body 105 member 15. A series of obtrusions 33 are formed along the flanges 28 and 31 and register to hold the two members together.

The plates 32 are formed with two horizontally aligned slots 34 and 35 which occur 110

each side of the upright portion of the base and receive trunnions 36 and 37 upon which guide rollers 38 and 39 are mounted to rotate. These trunnions are engaged by connecting links 40 and 41 which are secured by means of wrist-pins 42 and 43 to an adjusting disk 44, one of which is mounted within each end casing of the device and are secured to rotate together upon an actuating shaft 45 which extends through the center of the block and upon which each of the disks is fixed. In order to move the rollers toward and away from each other an adjusting member 46 is secured to one of the disks and is formed with a threaded shank 47 which extends outwardly through an arcuate slot 48 formed in one of the end plates 26. A nut is mounted upon the threaded shank and adapted to be tightened in a manner to lock the disk and rollers in a given position.

The rollers are provided as a guide for a polishing cloth 49 which is adapted to be passed over the top plate and have its opposite ends pass under the rollers on each side of said top plate for a purpose disclosed in Figs. 8 and 9 of the drawings. These rollers are cylindrical throughout the main portion of their length and are formed with conical portions 50 adapted to prevent the cloth from running off of the rollers and becoming fastened between the rollers and the end plate. The cloth may be of any preferred design. However, as illustrated in Fig. 5, the cloth is formed of a double strip of fabric material having reinforcing members 51 fixed in its opposite ends for use as a handle grip.

In operation, polish is placed upon the shoe in any preferred manner and the polishing cloth is then led in and around the rollers as described. The apparatus may then be placed upon a chair or other suitable support. A series of rubber knobs 52 are provided beneath the apparatus and protect the support. The toe of the shoe may then be polished by placing it upon the revoluble foot plate, as illustrated in Fig. 8. This is accomplished by first adjusting the rollers to the width of the shoe so that the polishing cloth will bear upon the entire surface thereof and then drawing the cloth backward and forward in a seesaw fashion until the desired luster is obtained. When it is desired to polish the instep and heel of the shoe as well as the top, the foot is moved forward so that the heel rests upon the revoluble plate and is held against slipping by means of tangs 53 which extend upwardly from the bottom of the foot plate. One end of the polishing cloth may then be led around the back of the shoe and the polishing motion continued, after which the ends of the cloth may be reversed to polish the opposite side of the heel and top.

The turning movement of the revoluble

foot plate 23 is limited by means of an arcuate slot 54 in the plate 21, and a pin 55 secured to the under face of the foot plate 23, which projects into said slot 54.

It will thus be seen that the shoe polishing apparatus here provided affords a rigid and convenient support for the shoe of the polisher during the operation and also provides effective means for holding the polishing cloth upon the surface of the shoe as well as permitting the device to be adjusted for use with shoes of different sizes.

While I have shown the preferred construction of my shoe polishing apparatus as now known to me, it will be understood that various changes in the combination, construction and arrangement of parts may be made by those skilled in the art without departing from the spirit of my invention.

I claim:

1. A shoe polishing apparatus, comprising a base, a horizontally disposed foot plate revolubly mounted thereupon, a pair of polishing cloth guide members disposed at opposite sides of said foot plate, and means for simultaneously adjusting said guide members horizontally in relation to each other and the plate.

2. A shoe polishing apparatus, comprising a base, an upright central portion formed thereon, a foot plate pivotally secured upon said upright portion, and uprights fixed at the opposite ends of said base, guide rollers disposed between said end uprights and upon opposite sides of said foot plate, locking means for adjustably securing said guide rollers in relation to each other, and means for simultaneously adjusting said rollers horizontally in relation to each other and the plate.

3. A shoe polishing apparatus, comprising a base having a central longitudinally extending upright formed upon it, a revoluble foot plate pivotally secured upon said upright, polishing cloth guide rollers disposed upon opposite sides of said upright, and members secured at the opposite ends of said base, means whereby said rollers may be revolubly and slidably supported by said end members, and adjustable means for simultaneously moving the rollers in and out from the central portion of said base.

4. A shoe polishing apparatus, comprising a base, a longitudinally extending upright portion mounted centrally of said base and formed with concaved sides, and uprights secured at the opposite ends of said base, a pair of polishing cloth guide rollers disposed between said end uprights and mounted one upon each side of the central upright portion, said uprights having horizontally alined slots adapted to receive the trunnions of the guide rollers, means whereby said guide rollers may be adjustably held

in relation to each other and moved toward and away from each other, and a foot plate revolvably mounted upon said central upright.

- 5 5. A shoe polishing apparatus, comprising a base, a horizontally disposed foot plate revolvably mounted thereupon, a pair of polishing cloth rollers disposed at opposite sides of said foot plate, said rollers being 10 formed with enlarged outwardly tapering end flanges adapted to act as a retaining guide for a polishing cloth, and means for simultaneously adjusting said rollers horizontally in relation to each other and the 15 plate.
6. A shoe polishing apparatus, comprising a base, a longitudinally extending upright portion disposed centrally of said base and formed with concave sides and uprights 20 secured at the opposite ends of said base, a pair of polishing cloth guide rollers disposed between said end uprights and mount-
- ed one upon each side of the central upright portion, said guide rollers being formed with enlarged tapering end flanges adapted 25 to retain the polishing cloth upon the rollers, said end uprights having horizontally alined slots adapted to receive the trunnions of the guide rollers, link members pivotally connected to the roller trunnions, operating 30 disks to which the adjacent ends of said link members are pivotally secured, a rod extending the length of the central upright portion and upon which the disks are fixed, means for rotating said disks to simultaneously move the rollers toward and away 35 from each other, a lock nut by which the rollers may be held in a desired position, and a foot plate revolvably mounted upon the central upright and adapted to support 40 the foot.

In testimony whereof I have signed my name to this specification.

A. C. ERICKSON.

Copies of this patent may be obtained for five cents each, by addressing the "Commissioner of Patents, Washington, D. C."
